Primary Examiner — Cynthia Underwood(57) **CLAIM**

The ornamental design for an object hanging apparatus, as shown and described.

DESCRIPTION

FIG. 1 is a perspective view of an object hanging apparatus showing my new design;

FIG. 2 is a front elevational view thereof;

FIG. 3 is a rear elevational view thereof;

FIG. 4 is a right side elevational view thereof;

FIG. 5 is a left side elevational thereof;

FIG. 6 is a top plan view thereof;

FIG. 7 is a bottom plan view thereof; and,

FIG. 8 is a perspective view showing the object hanging apparatus in an exemplary environment.

The broken lines showing a fence, a baseball helmet, a baseball glove and a baseball cap represent environment only and form no part of the claim.
